UNITED STATES PATENT OFFICE.

WILHELM BODLAENDER, OF BERLIN-HALENSEE, GERMANY.

PAPER-FILE.

1,084,839.

Specification of Letters Patent.

Patented Jan. 20, 1914.

Application filed May 28, 1913. Serial No. 770,465.

To all whom it may concern:

Be it known that I, WILHELM BODLAENDER, a citizen of the Empire of Germany, residing at Karlsruherstrasse 8, Berlin-Halensee, 5 Germany, have invented certain new and useful Improvements in Paper-Files, of which the following is a specification.

My invention relates to improvements in paper files in which the sheets of paper are 10 not punched but held by the clamping action of a pressure member.

The object of the improvements is to provide a paper file of this class which is simple in construction and reliable in operation.

15 With this object in view my invention consists in providing on the inner side of the file wrapper a hinged elastic bail provided with comparatively short side arms and made integral with an operating arm, which 20 is adapted to be locked in closing position by engaging below a locking nose, the said elastic bail clamping the sheets of paper by engaging the same at the rear of a clamping edge located below the sheets and in front of 25 the bail. The pressure which is thus exerted by the locking arm co-operates with the elasticity of the bail in such a way, that a reliable clamping action is produced with a full file as well as with a file which contains 30 a small number of sheets.

For the purpose of explaining the invention an example embodying the same has been shown in the accompanying drawing, in which the same letters of reference have 35 been used in all the views to indicate corresponding parts.

In said drawing Figure 1, is a plan view of the open file, Fig. 2, is a longitudinal section of the clamping mechanism of the file 40 taken with the cover or wrapper removed, and Fig. 3, is a cross-section taken on the line B—B of Fig. 1 with the cover removed.

To the inner side of the wrapper *a* a strip 45 of sheet metal *b* is secured which is bent upward at its outer end so as to produce an upturned clamping edge *c*. To the said strip *a* a pocket *d* of U-shaped section is secured, which is adapted to receive the sheets 50 of paper at the inner margins thereof. To the upper and lower ends of the strip *b* metal strips *e* and *f* are secured which at their inner ends are bent into the form of eyes providing hinge bearings for a bail *g*. The side arms *h* of the said bail are comparatively short, and they are so long, that 55

in the clamping position the bail acts on the sheets of paper at the rear of the clamping edge *c*. The end of the bail which is supported in the strip *e* has an extension or arm *k* which is bent at a right angle and is 60 formed at its end with a finger piece *i*, so that when depressing the arm *k* at its end *i* the whole length of the arm *k* operates by its leverage to press the bail *g* on the pocket or the papers placed therein. The bail *g* is curved downward, and by its elasticity 65 it is bent in such a way that it engages the sheets over the whole length of the same with uniform pressure, and that its clamping action is effective even in case the pile of 70 paper is but small. The strip *e* is provided with an upturned portion *l* formed with a nose *m* which is engaged by the arm *k* when depressing the same. When being thus depressed the said arm slides downward on 75 the inclined upper edge of the nose, and it is bent laterally, so that it engages by spring action below the nose.

In Fig. 3 the full lines show the bail in its clamping position, while the dotted lines 80 show the same in its open position in which the sheets of paper are released.

Fig. 2 shows the bail in the position in which it is in contact with the sheets of paper but is not yet pressed thereon and 85 bent into straight form.

In Fig. 1 the bail is shown in its clamping position.

I claim herein as my invention:

1. In a paper file, the combination with a 90 foundation providing a support for the sheets of paper, of an elastic bail curved toward the support and hinged thereto, an operating arm for said bail, and means to lock said arm in clamping position. 95

2. In a paper file, the combination with a foundation providing a support for the sheets of paper, of a strip on said support formed with an upturned clamping edge, an elastic bail curved toward the support and 100 hinged thereto, an operating arm for said bail, and means to lock said arm in clamping position.

3. In a paper file, the combination with a foundation providing a support for the sheets of paper, of a strip on said support formed with an upturned clamping edge, an elastic bail curved toward the support and hinged thereto and extending with its 105 clamping part at the rear of the clamping 110

edge, an operating arm for said bail, and means to lock said arm in clamping position.

4. In a paper file, the combination with a foundation providing a support for the sheets of paper, of an elastic bail curved toward the support and hinged thereto, an operating arm for said bail adapted to be pressed downwardly and laterally, and a

nose provided on the support and located in 10 position for locking engagement with said arm.

In testimony whereof I affix my signature in presence of two witnesses.

WILHELM BODLAENDER.
